CLAIM

The ornamental design for a controller for soldering iron as shown and described.

DESCRIPTION

FIG. 1 is a first perspective view of a controller for soldering iron showing a first embodiment of our new design;

FIG. 2 is a second perspective view thereof;

FIG. 3 is a front view thereof;

FIG. 4 is a rear view thereof;

FIG. 5 is a left side view thereof;

FIG. 6 is a right side view thereof;

FIG. 7 is a top view thereof;

FIG. 8 is a bottom view thereof;

FIG. 9 is an enlarged cross-sectional view taken along line 9-9 in FIG. 3 thereof, in which the internal mechanism is omitted;

FIG. 10 is an enlarged cross-sectional view taken along line 10-10 in FIG. 5 thereof, in which the internal mechanism is omitted;

FIG. 11 is a first perspective view of a controller for soldering iron showing a second embodiment of our new design;

FIG. 12 is a second perspective view thereof;

FIG. 13 is a front view thereof;

FIG. 14 is a rear view thereof;

FIG. 15 is a left side view thereof;

FIG. 16 is a right side view thereof;

FIG. 17 is a top view thereof;

FIG. 18 is a bottom view thereof; and,

(Continued)

FIG. 19 is an enlarged cross-sectional view taken along line 19-19 in FIG. 13 thereof, in which the internal mechanism is omitted.

The broken lines depict portions of the controller for soldering iron that form no part of the claimed design.
